(57) **CLAIM**

The ornamental design for a front face of a wheel, as shown and described.

DESCRIPTION

FIG. 1 is a front view of a front face of a wheel showing my new design; and,

FIG. 2 is an environmental perspective view thereof.
The broken line showing of the portion of the wheel other than its front face is for illustrative purposes only and forms no part of the claimed design.

1 Claim, 2 Drawing Sheets

FIG. 1

FIG. 2
